RECEPTACLE AND SOCKET FOR NEON
TUBES

William Ledder, St. Louis, Mo.

Application June 16, 1936, Serial No. 85,619

1 Claim. (Cl. 173—328)

The invention relates to a receptacle and socket for neon tubes and more especially to a fixture for neon tubes.

The primary object of the invention is the provision of a fixture of this character wherein the electrode of a neon tube will be properly held so as to avoid dampness from being present within the said fixture resulting from the collecting of foreign matter and insects which store dampness, the fixtures being of a novel construction so as to permit the quick drying out thereof and draining during inclement weather, so that the interior of the said fixture will be maintained dry and in this manner avoid the laying of the said electrode in water or dampness.

Another object of the invention is the provision of a fixture of this character wherein the electrode of a neon tube can be conveniently fitted therein and protected from weather element to assure constant dryness within said fixture.

A further object of the invention is the provision of a fixture of this character which is simple in its construction, thoroughly reliable and effective in its operation, enabling the convenient fitting of the electrode of a neon tube therein for protection of such electrode, strong, durable and inexpensive to manufacture and install.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing, Figure 1 is an elevation of a fixture constructed in accordance with the invention.

Figure 2 is a side view thereof.

Figure 3 is a vertical longitudinal section of the same.

Similar reference characters indicate corresponding parts throughout the several views in the drawing.

Referring to the drawing in detail, A designates generally a portion of a neon tube which is utilized in forming indicia of illuminated signs or the like and B the electrode end which is adapted for housing within a fixture or socket constituting the present invention and herein-after fully described.

The fixture is in the form of a receptacle 5 made from porcelain or the like and is of tubiform having a closed inner end 6 and an outer open end 7 respectively, the receptacle being tapered inwardly in the direction of the closed end 6 thereof. Internally of the receptacle and formed in its inner wall is a circular series of

substantially V-shaped ribs 8 providing therebetween substantially V-shaped channels or grooves 9 which extend throughout the length of the receptacle 5 and are cut through the open end 7 and meet the closed inner end 6 of said receptacle. These grooves 9 are deep at the open end 7 of the receptacle and gradually decrease in depth in the direction of the closed end 6 of said receptacle. 5

Formed in the receptacle 5 next to the closed end 6 thereof are laterally directed vents or openings 10 which are common to and communicate with the grooves 9.

Fitted centrally in the closed end 6 of the receptacle 5 is a binding post 11 for a wire (not shown) which supplies current to the electrode end B. This binding post 11 has engaged therewith a coiled expandable contact 12 for engaging the electrode end B when the latter is inserted within the receptacle 5 as is further shown in 20 Figure 3 of the drawing.

The grooves 9 internally of the receptacle 5 are for drainage purposes while the openings 10 are to assure ventilation through the receptacle to maintain the interior thereof dry. The electrode A at its end B when inserted within the receptacle 5 will be brought to settle onto the ribs 8 at the lowermost point of the said receptacle and it is practically impossible that this receptacle collect foreign matter, insects 30 which have a tendency to set up dampness internally of the receptacle and in the event of the collection, the same will become dry and free the fixture of moisture or resultant dampness and in this manner maintain the electrode 35 end B constantly dry.

Exteriorly of the receptacle A and integrally formed therewith are diametrically opposed attaching ears 13 while meeting these ears is an external shoulder 14, the ears being adapted to 40 permit convenient attachment of the fixture to a support with which the electrode or neon tube A is associated while the external shoulder gives reinforcement to the open end 7 of the receptacle. 45

What is claimed is:

A fixture of the character described comprising a tubular receptacle forming a socket closed at one end and open at its opposite end, said receptacle being tapered in the direction of 50 its closed end, and internal ribs formed from the side wall of said receptacle and longitudinally disposed therein for effecting drainage grooves therebetween, the ribs being parallel to each other at their apexes and the grooves gradually sloping from the closed end to the open end of the socket.

WILLIAM LEDDER.
